(57) **CLAIM**

The ornamental design for an automobile, as shown and described.

DESCRIPTION

FIG. 1 is a side elevational view of an automobile showing our new design;

FIG. 2 is a front and side perspective view thereof;

FIG. 3 is a rear and side perspective view thereof;

FIG. 4 is a front elevational view thereof;

FIG. 5 is an opposite side elevational view thereof;

FIG. 6 is a rear and opposite side perspective view thereof;

FIG. 7 is a rear elevational view thereof; and,

FIG. 8 is a top plan view thereof.

It will be understood that the broken lines shown in the drawings illustrate portions of the automobile that form no part of the claimed design.
